[57] CLAIM

The ornamental design for a cargo restraint, as shown and described.

DESCRIPTION

FIG. 1 is a perspective view of a cargo restraint showing my new design;

FIG. 2 is a side-elevational view thereof;

FIG. 3 is an end view thereof;

FIG. 4 is a top plan view thereof;

FIG. 5 is a bottom plan view thereof;

FIG. 6 is a cross-sectional view taken along lines 6—6 of FIG. 4;

FIG. 7 is a perspective view of a second embodiment of the design shown in FIG. 1;

FIG. 8 is a side-elevational view;

FIG. 9 is an end view thereof;

FIG. 10 is a top plan view thereof;

FIG. 11 is a bottom view thereof; and,

FIG. 12 is a perspective view of the cargo restraint of FIG. 7 shown in retracted position.
